Application March 8, 1935, Serial No. 9,977
Renewed August 9, 1937

7 Claims. (Cl. 209—310)

My invention has relation to improvements in screening devices and consists in the novel features of construction more fully set forth in the specification and pointed out in the claims.

5 The invention is particularly directed to a screening device for separating heterogeneous mixtures of material, such as city refuse which includes garbage, ashes, boxes, rags, papers, etc. While the invention is designed primarily for 10 the screening and separating of such material into graded sizes it will, however, be equally effective on other materials, such as crushed ore, coal, etc., and because of its ability to effectively handle heterogeneous mixtures it is even more 15 effective for rapidly and efficiently screening crushed masses of similar material.

The principal object of the invention is to provide a screen that will be subjected to a gyroscopic motion at its extremities to cause a vigorous 20 vibration or whipping movement of the screen elements which prevents the lodgment between screen elements of irregularly shaped pieces of material and pieces of limp material, such as rags. The motion of the screen is such 25 that should pieces of material being screened fasten themselves to the screen elements they will not long remain so fastened but will in a short time be shaken loose.

A further object of the invention is to provide 30 means for varying the degree of vibration imparted to the screen so that the screening effect may be regulated according to the material being operated on. The vibrating screen is also constructed in such a manner so that the violent 35 movement to which it is subjected is cushioned so that it will not be subjected to excessive wear, and so that it will not be communicated to the building in which the screen is installed.

The vibration and motion of the screen is 40 such that the grading action or screening of the material proceeds continuously without clogging. I find that this is accomplished most efficiently by vibrating the screen elements at a high rate of speed through a small amplitude which causes 45 the material to move down the inclined screen during the grading operation. Due to the heterogeneous character of the material and moisture content the particles have a tendency to stick together to form clots and some of the fine material 50 that should pass through the screen would be trapped in crumpled or crushed paper and other limp ingredients of the mass. The vibratory motion of the screen is such as to break up such clots and free the fine material from 55 other particles in which it may be trapped, and

at the same time prevent fine, moist material from adhering to the screen elements. The screen motion also prevents the wedging of lumps of material between the screen elements. In short, the construction of the screen together with the motion imparted thereto is such that the material is quickly and effectively spread over the entire screen and the grading proceeds so that the screen is at all times comparatively clean. 10

Preferably the upper and lower ends of the screen are not vibrated in unison, but have different vibratory periods or amplitudes so as to accentuate the whipping action of the individual screen elements, thereby introducing a differential of motion between adjacent elements which furthers the screening action and makes it practically impossible for lumps of material to become wedged between adjacent elements. In some cases it may be desirable to have the screen elements gyrate only at the upper end, and in other cases, to have the elements gyrate at both ends with the gyration at the lower end being through a smaller arc. 15

These objects, as well as the advantages inherent 25 in the invention, will be better apparent from a detailed description of the same in connection with the accompanying drawings, in which:

Figure 1 is a side elevation of my improved screen showing the middle part thereof broken away and the upper bearing support shown in section; Fig. 2 is a front elevation of the screen with the intermediate part broken away; Fig. 3 is a vertical, cross-section taken on a plane indicated by the line 3—3 in Fig. 1; Fig. 4 is a vertical, cross-section taken on the line 4—4 in Fig. 1; Fig. 5 is an enlarged longitudinal, sectional detail taken on the plane indicated by the line 5—5 in Fig. 3; Fig. 6 is an enlarged longitudinal, sectional detail taken on a plane indicated by the line 6—6 in Fig. 4; Fig. 7 is a horizontal section taken on a plane indicated by the line 7—7 in Fig. 1 with parts left in elevation; Fig. 8 is a cross-sectional detail of one of the brackets for supporting a screen element, 30 said section taken on a plane indicated by the line 8—8 in Fig. 5; Fig. 9 is an enlarged sectional view of a bearing and portion of the upper shaft of a modified form of the invention; Fig. 10 is an enlarged sectional view of a bearing and portion of the lower shaft of a modified form of the invention; Fig. 11 is a longitudinal, medial section through the lower end of a modified form of the screen; and Fig. 12 is a cross-section taken on a plane indicated by the line 12—12 in Fig. 11. 50 55

Referring to the drawings, 1, 1 represent concrete foundation members constructed in step shape, on the lower part of which are base castings 2, 2 and on the upper part base castings 2', 2'. The supporting surfaces 3, 3' of the base castings 2, 2' are inclined so as to give the desired inclination to the channel members 4, 4, 4, 4 on which my improved screen S is mounted. The screen comprises screening elements 5, 5, etc., carried 10 by upright arms 6, 6 at the upper end of the screen and 7, 7 at the lower end thereof, which arms are mounted on supporting shafts 8 and 9 at the upper and lower screen ends, respectively. The upper shaft 8 is supported in bearings 10, 10 15 carried by spring suspended plates 11, 11 of bearing supports 12, 12, and the lower shaft 9 is supported by bearings 13, 13 carried by spring suspended plates 14, 14 in bearing supports 15, 15. The bearing supports 12, 12 are securely bolted to 20 the upper ends of channel members 4, 4 and the bearing supports 15, 15 are securely bolted to the lower ends of said channel members.

The bearing supports 12 and 15 are similarly constructed and a description of one will serve 25 for all. Each of said supports comprises a box-like casting having side walls 16, 16 provided with centrally disposed recesses 17, 17 and laterally extending lugs 18, 18 at the ends of said side walls. The side walls also have horizontally disposed flanges 19, 19 adjacent their lower edges through each of which is a bolt hole 20 for receiving a bolt 21 by means of which the bearing support is secured to the channels 4, 4. There are bottom portions 22, 22 formed integrally between the side walls 16, 16, said bottom portions being spaced apart so as to leave the center of the casting open at the bottom.

In the upper surface of each bottom portion 22 is an annular depression 23 to serve as a spring 30 seat, and extending downwardly through the bottom portion and centrally disposed with respect to the spring seat is a square passageway 24 to receive the eye 25 of an eye-bolt 26. The eye bolts 26, 26 each have two superposed coiled springs 27, 27 disposed on them, and between the springs 27, 28 on the eye-bolts the bearing plate 11 is mounted. A spring cap 30 is disposed over the upper end of each spring 28, and nuts 31, 32 screwed over the threaded extremity 33 of the bolt 26 hold the bearing plate 11 firmly between the springs 27 and 28. The bearing plate 11 is provided with openings 34, 34 to accommodate the bolts 26, 26, and a pair of spring seats 35, 36 are formed around the openings 34 to accommodate both pairs of springs 27, 28 and hold them securely in place. A spring seat 37 is bolted to each pair of lugs 18, 18 at the ends of the bearing support casting through the opening 38 in which an eye-bolt 39 passes, the eye 40 at the inner end thereof being connected by means of a pin 41 between ears 42, 42 projecting from the end of bearing plate 11. A spring 43 is disposed over the bolt 39 and held in operative engagement with spring seat 37 by a spring cap 44 held 55 in place on the eye-bolt 39 by means of nuts 45, 46 screwed on the threaded extremity 41 of the bolt. The connecting of the eye-bolts 39, 39 between the ears 42, 42 permits the necessary pivotal movement to take place between these two parts 60 during the operation of the screw. The bolts 26, 26 are connected to the bottom members 22, 22 of the bearing support by pins 48, 48 disposed in the pin holes 49, 49 passing through the bottom members 22, 22 and intersecting with the openings 24, 24 therein. The eye-bolts 26, 26 are free

to move pivotally on the pins 48, 48 as required during the vibrations of the screen in operation.

The bearing plates 11, 11 and 14, 14 have roller bearings 10, 10 and 13, 13, respectively, mounted on them and secured in place by bolts 51. The ends 52, 53 of shaft 8 are mounted in the upper bearings 10, 10 and the ends 54, 55 of shaft 9 are mounted in the lower bearings 13, 13. It will be observed by referring to Figs. 3 to 6, inclusive, that both the upper and lower shafts 8 and 9 are unbalanced. That is, the shaft 8 has portions 56, 56 just inside the end portions 52 and 53 that are eccentric with respect to the balance of the shaft in that the center line x for these portions 56, 56 does not coincide with the center line x' of the balance of the shaft. On these eccentric portions 56, 56 of the shaft 8 the upper end of the screen S is carried by means of links or arms 6, 6, on the ends of which bearing boxes 59, 59 are formed for roller bearings 61, 61. A cross bar 62 in the form of a pipe is mounted in roller bearings 61, 61, said cross bar 62 carrying in juxtaposition a plurality of brackets 63 extending from one end to the other of the bar in contacting relation and maintained in position by collars 64, 64 fixed on the cross bar 62 by means of set-screws 65, 65 just inside the bearing boxes 59, 59.

The upper ends of the screen elements or bars 5 are each enveloped by a sleeve 66 and rest on a concave seat 67 formed on the upper end of each bracket 63. A flange 68 extends rearwardly from the bracket 63 and is perforated as are the screen element 5 and sleeve 66 to receive a bolt 69 which secures the upper end of the bar firmly to the bracket 63. As stated above, the shaft 9 is also unbalanced as the portions 70, 70 are eccentric with respect to the balance of the shaft, as indicated by the center lines y and y'.

Bearings boxes 71, 71 are mounted on the eccentric portions 70, 70 of the shaft 9 and are each provided with upwardly presented flanges 72, 72. The flanges 72, 72 of the bearing boxes 71 support a cross member 73 having angle pieces 74, 74 at its ends which rest on the flanges 72, 72 and are secured thereto by means of bolts 75, 75. The cross member 73 is in the form of a T-beam and carries the lower ends of the screen elements 5. Sleeves 76 are disposed over the lower ends of said screen elements and a bolt 77 passes through the sleeve 76, element 5 and outer flange of the cross bar 73. It will be observed that the upper sleeves 66 and lower sleeves 76 contact with each other so as to effectively space the screen elements 5 from each other.

On the extremity 53 of the shaft 8 and the extremity 54 of shaft 9 are mounted pulleys P, P', respectively, so that these shafts are driven independently of each other. Thus either shaft may be rotated, the other remaining stationary, or the speed of either shaft may be varied so as to regulate the action of the screen according to the material that is being screened.

In the operation of my improved screening device the rotation of the shafts 8 and 9 will impart a gyratory motion to the links 6, 6 and bearing housings 71, 71 since, as explained above, these members are mounted on eccentric portions of the shafts. This gyratory motion will of course be imparted to the ends of the cross bar 62 and the ends of cross member 73 communicating the gyrations to these members. Since the screening elements 5 are carried on the members 62 and 73 they will be vigorously vibrated by the gyrations of their supporting members, and owing to their length will also undergo a certain

amount of whipping motion so that no two bars will necessarily vibrate in unison. In other words, while the screening elements 5 all receive their motion from the same actuating members they 5 will move more or less independently and thereby produce a very effective screening action. I have found that this vibrating, whipping motion of the bar 5 is very effective in preventing limp pieces of material, such as rags, from becoming 10 fastened to the bars, and if such pieces of material should become wrapped around any of the bars it will in a short time be again dislodged.

Since each end of the screen is independently actuated the lower end may be vibrated at a high 15 rate of speed with comparatively small amplitude, while the upper end may be oscillated at a comparatively slow speed with relatively large amplitude. Owing to the link support at the upper end of the screen the motion of the lower 20 end will be substantially parallel to the plane of the screen. The character of the motion imparted to the lower end of the screen may be varied by adjusting the tension of the vertical springs 25 26, 27 and horizontal springs 43 from an elliptical motion with the major axis of the ellipse parallel to the plane of the screen to an elliptical motion with the major axis of the ellipse perpendicular to the plane of the screen, or at any angle between these two extremes. The upper end of 30 the screen will be oscillated in a direction parallel to the plane of the screen with a large amplitude compared to the lower end of the screen so that the material near the upper end of the screen will not merely slide along the screen but will be 35 jogged downwardly. Due to the link connection at the upper end of the screen and the pivoted connection at the lower end, the motion created by the unbalanced shaft 8 at the upper end of the screen will gradually decrease in amplitude 40 downwardly of the screen until it finally disappears at the lower end of the screen.

When the two ends of the screen are actuated at the same time the vibratory motion imparted by the lower shaft will be superimposed upon the 45 jogging or oscillating motion imparted by the upper shaft, and the screen as a whole will undergo a vigorous, irregular whipping motion in combination with the vibration and oscillation. The jogging at the top of the screen will be effective to loosen up clumps of moist material and fine material that may be entrapped in crumpled paper, rags, or similar pieces, and will also quickly spread the material over the entire screen, producing a rapid and regular screening action. 50 The vibratory motion and the whipping action operates effectively to prevent the moist, fine material from sticking to the bars, and coarser lump material from becoming wedged between the bars. The vibratory motion of the small amplitude 55 will also contribute largely to maintaining the continuous screening action and feeding the material downwardly along the screen. Since this vibratory action is most prominent at the lower end of the screen it will allow the coarser material to lie close to the bars and settle into slots after the finer material has passed through further up on the screen.

In summing up, the following are some of the conspicuous characteristics of the screen: 70 1. Possesses a jogging and vibratory action with a superimposed irregular whipping of the bars essential to the grading of a mixture composed of materials differing widely in physical characteristics. 75 2. The differential of movement between the

bars prevents material from becoming wedged, and also prevents limp material, such as rags, from working down the screen without being graded.

3. The jogging action will loosen up adhering material and cause the smaller material to quickly settle down and pass through the screen elements.

4. The variability of the motion at the lower end of the screen by the adjustment of the 10 springs makes it possible to cause the material to move either more rapidly or slowly as it approaches the bottom of the screen.

The vertical springs 35 and 36 also serve to cushion the vertical thrust produced by the operation of the screen and the horizontal springs 15 43, 43 likewise absorb the longitudinal thrust so that the vibrations of the screen will not be imparted to the supporting structure or building containing the same. 20

In the modification shown in Figs. 9 and 10 the construction of the upper and lower shafts 30 30 and 31 is slightly different. Instead of having a shaft formed with eccentric journal portions 56, 56 for the upper shaft and 70, 70 for 25 the lower shaft, as in the main form, the shafts are now unbalanced with respect to their rotation axes; that is, the entire shaft 80, between the journal portions 82, is eccentric with respect to the end portions of the shaft, and the entire 30 shaft 81 between the journal portions 84 is eccentric with respect to the extremities of the lower shaft. Since the extremities of the respective shafts 80 and 81 are mounted in their respective spring suspended bearings 10 and 13 35 35 the unbalanced portions of the shafts will cause a violent vibration and impart a vertical reciprocation or gyration to the screen carried on them.

In the modification shown in Figs. 11 and 12 the lower ends of the screen elements or bars 5 40 40 are mounted on saddles 85 supported from the supporting plate 86 by upwardly extending webs 87. The webs 87 are of substantial height so as to elevate the bars considerably above the supporting plate 86 which has terminal flanges 88, 45 45 by means of which the plate 86 is secured to the bearing housing 71. The bearing plate 86 is curved downwardly to the rear for the purpose of expediting the discharge of fine material passing between the bars 5 and dropping on said 50 plate. Any rags or limp material *m* that ride down on the bars 5 encounter no obstructions by virtue of the elevated saddles 85 and are free to slide off the ends of the bars. However, should pieces of material fall between the bars and 55 lodge on the plate 86, the quick vibratory movement to which this plate is subjected will gradually propel such pieces forwardly over the plate as indicated (Fig. 11).

Having described my invention, I claim: 60

1. A screening device comprising an upper and a lower pair of bearing supports, bearings in said supports, cushioning means interposed between each bearing and its support, a transversely disposed shaft mounted in each pair of bearings, a 65 screen carried by said shafts, said screen comprising a plurality of bars individually mounted, screen supporting journals in spaced relation on each shaft, suitable connecting members between the screen and shafts and swiveled on the 70 journals thereof, and said journals being eccentric with respect to the rotation axis of their respective shafts.

2. A screening device comprising an upper and a lower pair of bearing supports, bearings in 75

said supports, cushioning means interposed between each bearing and its support, a transversely disposed shaft mounted in each pair of bearings, a screen carried by said shafts, said screen comprising a plurality of individually supported bars, means for rotating said shafts, and said shafts being unbalanced so as to gyrate the screen supports on rotating the shafts.

3. A screening device comprising an upper and 10 a lower pair of bearing supports, bearings in said supports, cushioning means interposed between each bearing and its support, a transversely disposed shaft mounted in each pair of bearings, a screen carried by said shafts, said screen comprising a plurality of individually supported bars, 15 means for independently rotating said shafts, and said shafts being unbalanced so as to gyrate the screen supports on rotating the shafts.

4. A screening device comprising an upper and 20 a lower pair of bearing supports, bearings in said supports, cushioning means interposed between each bearing and its support, a transversely disposed shaft mounted in each pair of bearings, a screen carried by said shafts, suitable connecting 25 members between the screen and the shafts, means for rotating said shafts, and said shafts being unbalanced so as to gyrate the screen supports on rotating the shafts, said screen comprising a plurality of juxtaposed bars of relatively 30 small diameter compared to their length so as to undergo a whipping action during the gyrations of the screen supports.

5. A screening device comprising an upper and 35 a lower pair of bearing supports, bearings in said supports, cushioning means interposed between each bearing and its support, a transversely disposed shaft mounted in each pair of bearings, a screen carried by said shafts, screen supporting journals in spaced relation on each shaft, suit-

able connecting members between the screen and shafts and swiveled on the journals thereof, said screen comprising a plurality of juxtaposed screen elements individually supported by the connecting members at one end of the screen, and said 5 journals being eccentric with respect to the rotation axis of their respective shafts.

6. A screening device comprising an upper and a lower pair of bearing supports, bearings in said supports, cushioning means interposed between 10 each bearing and its support, a transversely disposed shaft mounted in each pair of bearings, a screen carried by said shaft, screen supporting journals in spaced relation on each shaft, suitable connecting members between the screen and 15 shafts and swiveled on the journals thereof, said screen comprising a plurality of juxtaposed screen elements individually supported by the connecting members at the upper end of the screen and collectively supported by the connecting members 20 at the lower end of the screen, and said journals being eccentric with respect to the rotation axis of their respective shafts.

7. A screening device comprising an upper and a lower pair of bearing supports, bearings in said 25 supports, springs suspending the bearings in a manner to absorb the vertical thrust thereon, and springs between the ends of the supports and bearings to absorb the end thrust thereon, a transversely disposed shaft mounted in each pair 30 of bearings, a screen carried by said shafts, screen supporting journals in spaced relation on each shaft, suitable connecting members between the screen and shafts and swiveled on the journals thereof, and said journals being eccentric with 35 respect to the rotation axis of their respective shafts.

JOHN E. GREENAWALT.
